ABSTRACT

A photographic processing web imbiber and method for imbibing in which the web is wound from a first reel to a second reel through a fluid-soaking bath in loose enough winds to allow the liquid to continue being absorbed by the web while wound on the reel and having a final wind tight enough to squeegee out the liquid phases of materials in the final wind.

METHOD AND APPARATUS FOR TESTING A PROCESSING WEB

This invention relates to a machine for and method of impregnating Bimat transfer film with processing solution.

The Bimat film process currently distributed by Eastman Kodak involves a system in which a photographic film is exposed in the conventional manner in conventional photographic cameras and thereafter the film is placed in face to face contact with a film or processing web called a mat impregnated with a processing solution. The result upon separating the mat and the film is in a processed negative image on the film and a processed positive image on the mat. As distributed, the mat is in a dry form and is normally imbibed or presoaked in processing solution shortly prior to its use in processing. The presoaking or imbibing of the mat shortly before the processing is necessitated by the relatively short shelf life of the presoaked mat material. The imbibing or presoaking of mat material must be accomplished under controlled, fixed, physical conditions but can normally be accomplished under ambient light. The controls required necessitate the control of temperature, the amount and concentration of solution, the timing at various phases and for the application of hardener and control of tightness of wind of the mat in the final wind. Variations in the controls result in either unsatisfactory or irregular processing.

The principal object of this invention is to provide a novel method of and means for presoaking the processing web or mat film in such a manner as to provide an imbibed mat which has uniformity of processing solution impregnation of requisite hardness and is wound in a manner on the reel which will resist damage during storage.

In the present invention, the dry mat film is passed between horizontal reels through a processing solution bath in which the various passes through the bath from one reel to the other is accomplished with a loose wind on the takeup spool, except on the final wind which is accomplished with a tight wind.

As a further control in the present invention, the temperature of the processing solution is regulated for optimum pickup during passes of the film through the processing solution and on the last pass the temperature is reduced to prevent thermal contraction of the convolutes in the final wind. As a still further control, the speed of the winds is sufficiently rapid to cause the majority of processing mat interaction to occur on the spool while wound in the helical configuration. In still another control in the process, the hardener which functions to harden the mat emulsion is applied with such rapidity that the hardening action does not occur until the film has been tightly wound onto the final takeup spool.

One feature and advantage of this invention lies in the fact that the mat material picks up the liquid processing solution in the bath for delivery to the convolutes due to the loose wind of the reel during takeup to prevent squeezing action of the processing solution during the winding phase.

A further feature and advantage of this invention lies in the fact that the device is operated at sufficient speed so that the time that the mat film remains in the solution is kept at a minimum, thereby causing the vast majority of physical and chemical interaction on the mat to take place primarily on the reel rather than in the solution bath.

A still further object of the invention is to provide a reel arrangement in which the reels are maintained in a horizontal position to prevent accumulation of processing solution from migrating to one edge of the rolled mat film.

In the present invention, the last pass of the film through the processing solution is accomplished with a chemical hardener being added to the processing solution and with the temperature of the processing solution being lowered to at least below the ambient temperature conditions under which the mat material is to be used or stored. Under these conditions, the mat is driven rapidly and under controlled tension from the supply to the takeup reel through the bath. The aforesaid method and apparatus affords the advantage of causing liquid phase processing solution to be squeezed from the reel as it is

being wound and further causes additional liquid phase processing solution to be absorbed by the mat while on the tightly wound convolutes of the takeup reel before the action of the hardener is realized.

5 A still further feature and advantage of the method and process above set forth lies in the fact that the final bath is maintained at lower or near ambient storage or processing temperature conditions to prevent thermal contraction.

10 Because of the aforesaid features and advantages, there is a substantial reduction of dry spots which otherwise occur in other methods of imbibing.

15 As a further feature and advantage of this invention, the structure afforded is adaptable to operate with a relatively low volume of processing solution so that not only can the quantity of chemicals employed be conserved but also relatively low volumetric capacity affords an easier media for control of the temperature conditions of the solution.

20 Other objects, features, and advantages of the present invention will be more apparent after referring to the following specification and attached drawings in which:

FIG. 1 is a schematic view showing the apparatus for imbibing the mat film;

FIG. 2 is an enlarged fragmentary sectional view showing the mat material being loosely wound during imbibing;

25 FIG. 3 is an enlarged view showing the mat material being tightly wound during imbibing;

FIG. 4 is a fragmentary view showing convolutes of a mat having spatial areas due to improper imbibing; and

30 FIG. 5 is a schematic view of another embodiment of the invention showing the imbibing apparatus in which the tank is vertical rather than horizontal.

35 Referring to the drawings, there is provided a Bimat presoaker or imbibing apparatus generally indicated at A having a horizontally disposed solution tank B. Mat spindles 20 and 21 are mounted for rotation horizontally over tank B by bearings 24 and 25 which are driven by motors 26 and 27 respectively for rotation of the spindles selectively in opposite directions.

40 Photographic mat material of the Bimat type is mounted for passage between reel 30 on spindle 20 and reel 31 on spindle 21 with the mat passing over two idler rollers 33 and 34 mounted in tank B. The rollers establish a straight stretch 35 of mat material which passes through the solution in tank B between the two rollers 33 and 34 as the mat is transferred from reel 30 to reel 31 and vice versa. Rollers 33 and 34 are also mounted on bearings to render them as free of friction as possible.

45 50 Processing solution is entered and withdrawn from tank B via two conduits 36 and 37 mounted at one end of the tank.

The bottom portion of the tank is formed with a heating and cooling structure 40 which is controlled to provide predetermined temperatures by a temperature controller 41. The heating-cooling unit 40 may take the form of a single or composite unit which may on the one hand include an electrical heating unit and companion refrigeration coils or may simply consist of thermoelectric units which are capable of both raising or lowering the temperature in proportion to the power or polarity of the electrical input into the heating-cooling unit.

55 60 Mat C conventionally can be of the dry Kodak transfer film (Estar Base) Type SO-111 or SO-160 which normally are available in dry states. Such films when properly soaked with processing solution are then ready for processing by combining the mat material with film.

65 70 Dry unsoaked Bimat, as distributed, can be stored for long periods. After presoaking, as is accomplished in the present invention, there is a limited shelf life; therefore, in normal practice, the mat material is soaked shortly prior to intended use.

In operation, a reel of mat material is mounted on spindle 20 and then threaded around idler rollers 33 and 34 for attachment to spindle 21 to form the two spools or reels 30 and 31. The processing solution is then added through conduit 36 into tank B at a liquid level which is substantially above film

stretch 35 so that the entire stretch is submerged in the processing solution. Temperature controller 41 is employed to raise the temperature of the solution to the optimal temperature for creating adequate imbibing action with the mat which is usually in the range of between 90° to 110° F. Under these conditions, the film is transported from reel 30 to 31 at speeds ranging an average of 25 to 175 feet per minute. Thereafter, the mat in reel 31 is transferred back to reel 30 at the same speed. The respective transfer between the two reels is then repeated several times until adequate absorption of the processing solution in the mat is accomplished.

In the final wind, the temperature through temperature cooling unit 40 and the control of temperature controller 41 is dropped to a level approximately equal to the temperature at which it is intended that the soaked mat material be stored. A hardener is added to the processing solution for the last pass. It is important in the present invention that during all except the last pass that the transfer of the mat from the supply of the two reels to the takeup be under conditions of minimum impedance so that the mat will be in as loose convolutes on the takeup reel as possible.

The film traveling at relatively high velocities for a relatively short length through the processing solution will result in the liquid phase processing solution being carried by the mat onto the takeup reel. Because of the loose wind effected by low impedance or drag, there is minimal squeegeeing or compressive elimination of the liquid phased developer as the film is wound onto the takeup reel. Thus, the soaking or absorption of the processing solution onto the film or mat occurs mainly while the mat is wound in convolutes on the takeup reel. The passage through the processing solution functions mainly to create pickup of liquid phase processing solution and the looseness of wind functions to maintain the liquid phase processing solution on the mat while it is being wound onto its respective convolutes. Mechanically, the aforesaid configuration is accomplished by providing bearings 24 and 25 of sufficiently frictionally free construction to allow minimum drag. This is also true of the two idler rollers 33 and 34. Alternatively, the same can be accomplished by establishing a powered overdrive for the supply of the two reels through energization of motors 26 or 27.

By accomplishing the combination of the steps in this manner, the amount of processing solution carried to the convolutes remains consistent through each pass. The processing solution absorbed by the mat is not the result of absorptive activity while the mat material is in transit through the processing solution bath but is rather the result of absorptive activity while the mat is spooled.

It is also noted that the reels are mounted in a horizontal position and by virtue of the horizontal placement the flow of liquid phase processing solution in the convolutes is maintained constant throughout the mat in that there is no gravity urging of the fluid towards one end or the other which would occur if the reels were mounted for vertical rotation.

In the final wind, as has been previously explained, the supply of the two reels is supplied with sufficient brakeage or resistance to provide considerable tension and stress for the winding onto the takeup of the two reels. Under these conditions, as can be seen in FIG. 3, the pressure of the outer convolutes causes liquid phased processing solution to be squeegeed out of the mat as it is being rolled onto the reel. This is important in that in the final phase it is desirable to have both a tight and a nonliquid phase condition. Should there be the presence of liquid phase in the finally wound reel, there is likelihood that evaporation of unabsorbed liquid phase processing solution will result in bubbles or gaps as indicated at 48 in FIG. 4. Such gaps will undesirably affect processing when eventually combined with photographic film.

The tension afforded on the final wind can be accomplished by providing a brake mechanism for the supply spindle or, alternatively, the respective motor drive for the supply spindle can be back driven.

5 Hardener is added on the last pass. The hardener action when culminated hardens the emulsion which inhibits further absorption of liquid onto or into the mat. By running the mat swiftly through the combination processing solution and hardener, it can be seen that the wind onto the final takeup spool or reel occurs prior to the chemical hardening activity taking place. Thus, any liquid phase remaining in the final wind can be absorbed while the mat is in tightly wound relation and prior to the time that the hardening action sets up to provide an absorption inhibitor.

10 As has previously been explained, the temperature on the final pass is dropped to the proposed storage temperature of the mat material. This is important to provide a preconditioning of the soaked mat to a temperature commensurate to the ambient temperatures at which the mat is to be stored. It has been found that if the soaked mat is substantially lowered in temperature after being imbibed, air pockets 48 of the type shown in FIG. 4 may develop. It is reasoned that this occurs because of thermal shrinkage of the mat under lower temperature conditions. Thus, maintaining the final passage of the mat through the processing solution under temperature conditions which are as low as or near the temperature for storing, the mat will result in superior mat imbibing.

15 20 25 As an alternative embodiment of the present invention, the mechanism can be arranged as shown in FIG. 5 in which a supply reel 60 is arranged to pass mat C vertically around a guide spindle 61 to a takeup spindle 62. Spindles 60 and 62 can alternatively, as in the preceding embodiment, be employed as takeup and supply spindles and are provided with appropriate friction free bearings and power drive units as disclosed above in reference to FIG. 1. A heating and cooling unit 70 can be placed along the side of the processing solution bath 72. The device in this embodiment functions in exactly 30 35 the same way as that shown in relation to FIG. 1.

While one embodiment of this invention has been shown and described, it will be apparent that other adaptations and modifications can be made without departing from the true spirit and scope of the invention.

40 What is claimed is:

1. A mechanism for soaking a photographic processing web comprising a pair of spaced-apart, horizontally mounted spindles adapted to function as hubs for a photographic processing web and on which a photographic processing web is mounted 45 to extend between the spindles, means for driving at least one of said spindles for rotation at a controlled rate, bearing means for rotatably mounting at least the other of said spindles for substantially friction free rotation, a liquid bath of photographic processing solution mounted below said spindles, means to guide said web wound on one of said spindles through said bath to the other of said spindles for coiling of the web only about itself on the other spindle, said guide means including means providing a minimum of frictional impedance to the web, the combined frictional impedance of the bearing means and the guide means being low enough to cause coiled convolutes resulting from winding the web on the drive spindle to be sufficiently loose to enable the liquid from the liquid bath carried by the web to be retained between adjacent convolutes without being substantially squeezed therefrom.

50 55 60 65 2. The mechanism according to claim 1 and wherein said drive means are mounted to each of said spindles and wherein free rotatable bearing means are similarly mounted with each of said spindles, said drive means and said bearing means being alternatively engageable with each of said spindles to allow the web to be freely transported to and fro between said spindles with the supply of the two spindles being substantially, frictionally free to rotate and the takeup of the two spindles being driven by the drive means.

70 75 3. Apparatus for subjecting a photographic processing web to a liquid solution for a predetermined length of time comprising: first and second hubs mounted in spaced relation and adapted to be in respective engagement with a length of said web only for movement of the web therebetween at a predetermined speed; low friction bearing means for mount-

ing at least the first hub, the low friction bearing means enabling a substantial friction free rotation of the hub to maintain said web reeled off the first hub substantially tension free; a bath holding the solution; low friction guide means intermediate the hubs guiding the web through the bath for applying the liquid solution to the web, the guide means being arranged so that the web moving at the predetermined speed contacts the solution in the bath for less than the predetermined length of time, the guide means being further selected to maintain the web downstream of the guide means substantially tension free; and drive means operatively coupled to the second hub for winding said web only after immersion of the web in the bath on the second hub in loose convolutes forming spaces between adjacent convolutes retaining solution therein contacting the web, to thus soak the web for the predetermined time while loosely wound and removed from the bath.

4. A method for soaking a photographic processing web in a photographic processing solution for a predetermined time period during a treatment phase, the method comprising the steps: reeling the processing web off a first spindle while maintaining the reeled off web substantially tension free; guiding the reeled off web over substantially frictionless guide means through a solution bath so that the web reeled off the first spindle and disposed in the solution is substantially tension free; retaining the web in the bath for a time period shorter than the predetermined time period; and winding the soaked web only about itself onto a second spindle in loose convolutes

while photographic processing solution is carried on the web to retain photographic processing solution between adjacent convolutes of the coiled film on the second spindle and soak the web in the solution for the predetermined time period 5 while the web is coiled and removed from the bath.

5. A method for soaking a processing web according to claim 4 and having a second treatment phase including the further step of passing the web through the solution and then 10 immediately winding the web onto one of the two spindles under sufficient tension to cause a squeegeeing out of a substantial portion of the photographic processing solution as the web is wound on the spindle.

6. A method for soaking processing web according to claim 5 having the steps of regulating said solution to a temperature 15 for efficient absorption during said first mentioned treatment phase and cooling said solution to a temperature at least below the temperature at which the web is to be subsequently stored prior to execution of the second treatment phase.

7. A method for soaking a processing web according to 20 claim 5 having the step of cooling said solution to a temperature at least below the temperature at which the web is to be subsequently stored prior to execution of the second treatment phase.

8. A method for soaking a processing web according to 25 claim 5 and having the steps of adding a hardener to said solution only during said second treatment phase.
